AXIS CONVERTER

Paul M. Birk, Williamsville, N. Y., assignor, by mesne assignments, to the United States of America as represented by the Secretary of the Army

Application February 27, 1953, Serial No. 339,279

15 Claims. (Cl. 33—46)

The present invention relates to an axis converter. With the introduction of air warfare and defense by anti-aircraft, and in view of the high speed of modern aircraft, mechanical aids for fire control have been supplanted by automatic means for making computations with sufficient rapidity to satisfy the speed requirements. One such device is the director which comprises means for continuously observing optically the elevation and azimuth of a target, and including automatic means utilizing electrical circuits to make the necessary computations and to translate them into gun settings.

In operating the director observations are taken, and from these observations the director makes all the necessary computations and transmits the results in suitable form for directing the guns. The calculations, as indicated, are made continuously, and without delay and with a high degree of accuracy, so that the guns may be fired at any instant after computations are made and as long as the target is within range. The director operator optically observes at a given instant the azimuth and elevation of the target with respect to a horizontal plane. Other means such as an optical height finder, or radar are used to obtain the range or height of the target at that same instant, and the mechanical movements of the director in making the necessary observations then are translated into electrical impulses.

Commencing with the basic assumption that the target will continue to move in a straight line at constant speed while the projectile is in flight, the necessary calculations are made automatically and transformed into terms of firing azimuth, quadrant elevation, and fuze setting required to direct a gun battery so that at a predetermined time interval after the observations are made a fired projectile and the target will meet at the same point in space, whereupon the projectile will explode to destroy the target.

In the known directors, the observed azimuth and elevation readings are taken with respect to the ground. However in certain circumstances, when greater accuracy in locating the future position of the target is desirable, the conversion of the azimuth and elevation readings to a vertical plane perpendicular to the ground has been found to be of great assistance in more accurately locating the present position of a target moving in space.

In addition to providing the means for more accurately predicting the present position of a target moving in space the axis converter is also used to alter the flight course of a guided missile so that the missile may be steered to a fixed target. In this situation the missile is provided with a control system actuated by a signal sent from the ground. In order to furnish the missile with the proper signals to alter its course, it is necessary to supply information in regard to both pitch and yaw. In actual practice, therefore, the gun director modified by the addition of the axis converter, gives azimuth and elevation angles both with respect to the ground, and

with respect to a plane perpendicular to the ground. This information is then sent to a computer which in turn feeds a transmitter, and sends a signal to the missile in flight so that the missile will follow a course desired by the operator of the gun director.

In addition to the four angles, it is also necessary to feed into the computer information as to the exact location of the target toward which the missile is headed.

It is accordingly an object of this invention to provide means for converting azimuth and elevation readings of a director to a vertical plane perpendicular to the ground.

It is also an object of this invention to provide mechanical apparatus integral with the structure in a director upon which the telescope is mounted, for transforming azimuth and elevation reading with respect to the ground, to a vertical plane perpendicular to the ground.

It is also a further object of this invention to provide a linkage supportable upon brackets made integral with the azimuth gear forming part of a rotating head for a director. The linkage is responsive to movement of the rotating head in azimuth and the observing telescope in elevation to respectively rotate an output shaft and to slide a second shaft within the output shaft to thereby give azimuth and elevation angles relative to a vertical plane perpendicular to the ground.

With these and other objects in view which will become apparent as the specification develops, reference is made to the accompanying drawing forming part of the specification wherein like numerals have been used to designate corresponding or similar parts and wherein:

Figure 1 is a view in perspective of the axis converter linkage forming part of a rotating head of a director.

Figure 2 is a diagram illustrating the input azimuth and elevation angles with respect to a horizontal or ground plane and the corresponding angles as transformed by the converter to a vertical plane perpendicular to the ground plane.

Referring to the drawings reference character 1 designates a portion of the tracking head comprising a platform or plate 2 which is rotatable in azimuth about a vertical or "azimuth input" axis Y—Y with respect to the ground, by an operator. Plate 2 is peripherally notched as at 3 to form an azimuth gear for transferring azimuth positions to synchro units (not shown) which in turn transmit azimuth or gun train orders to a gun mount or computer. A pair of diametrically opposed upstanding support members 4 and 5 are secured to the upper face of plate 2, and are provided with horizontally aligned holes 6 and 7 in which is journaled a shaft 8, upon which is integrally mounted an observing telescope 9. On the extreme ends of shaft 8 are mounted gears (not shown) for driving synchro units (not shown) which transmit elevation orders to a gun mount or computer.

55 The support structure for the axis converter linkage comprises a pair of diametrically opposed downwardly extending brackets 10 and 11 each having one end secured in any convenient manner to the lower face of plate 2 and with the free lower ends provided with horizontally aligned holes 12 and 13 into which is journaled a transfer shaft 14. Brackets 10 and 11 are in vertical alignment with upwardly extending supports 4 and 5 so that transfer shaft 14 is always normal to the "input azimuth" axis, and parallel to and in vertical alignment with telescope shaft 8.

60 It can readily be seen therefore, that when plate 2 and shaft 8 are moved in azimuth, transfer shaft 14 also moves accordingly. Means are also provided to correspondingly rotate transfer shaft 14 in elevation to follow a like movement of telescope 9 and shaft 8. This means comprises a first pinion 15 concentric about shaft 8 and integral therewith, and second pinion 16 in like manner integral with transfer shaft

14, and vertically aligned with pinion 15. Plate 2 is provided with a central hole 17 through which extend vertically reciprocable push-pull rods 18 and 19 having respectively upper and lower racks 20 and 21 each engaging pinions 15 and 16 on one side, and upper and lower racks 22, 23 engaging pinions 15 and 16 on diametrically opposed sides. As the telescope is moved in elevation, transfer shaft 14 rotates accordingly due to the action of the above described action of the push-pull rods on the racks and pinions. The axis of rotation of the transfer shaft may be designated the "input elevation" axis X—X.

The converter linkage per se comprises a pair of parallel elongated arms 25, 26, each having one end mounted on transfer shaft 14, such that arms 25 and 26 are always parallel to the line of sight of the telescope, and the free ends apertured as at 27, 28 to receive a pivot pin 29, upon which are in turn mounted downwardly extending parallel links 30, 31 having a shape somewhat as a "boomerang," and which are apertured at their extreme ends as at 32, 33. Received in these latter holes are pivot pins 34, 35 extending outwardly from opposed sides of a hexahedral block or gimbal 36, provided with an axial bore 37, normal to the axis of pins 34, 35, for receiving with a smooth fit a stud or pin 38 forming an elongation of the larger leg 39a of a bell crank member 39. By this construction, the arm 39a of bell crank 39 may pivot in block 36 about the axis of its reduced end or pin 38, and may pivot about the axis of pins 34 and 35 in a plane midway between the links 30 and 31. The extreme ends of pins 34, 35 are threaded to receive nuts 40 (one shown) to maintain gimbal 36 secure between links 30, 31. The free end of pin 38 is also threaded to receive a nut 41, such that when the linkage is assembled, little or no clearance is provided between abutting faces of gimbal 36 and bell crank member 39.

The axis converter also includes a cradle structure 24 for mounting elements which cooperate with the above described linkage to define the "output" axes, or the axes which correspond to the azimuth and elevation measurements relative to a vertical plane perpendicular to the ground. This structure comprises horizontally spaced vertical end plates or support brackets 42, 43 secured to a base plate (not shown). The base plate in turn is secured to the base (not shown) of the director, which is non-rotating. The end plates 42, 43 are provided with horizontally aligned holes 44, 45 in which are journaled stud shafts 44a and 45a forming a second transfer shaft which defines an axis of rotation for cradle 24 which may be termed the "output azimuth" axis Y'—Y'. A built up metal plate construction 47 forming part of cradle 24 comprises an upwardly opening box structure extending from end plate 42 for approximately two-thirds the distance to end plate 43, and includes a channel member 48 having turned up sides 49 and a left end 50 also turned up so as to have a depth equal to approximately twice the depth of sides 49, adjacent bracket support or end plate 42. The opposed end of box 47 is covered by a plate 51 to complete the box, and a U-shaped strap or support member 52 is secured in any convenient manner to the outside surfaces of turned up sides 49 and 50. To the outer surface of box end 50 and above strap 52 is secured a support plate or bearing plate 53 to abut the inner surface of end plate 42, and to this plate is affixed stud shaft 44a to extend through hole 44 in plate 42. The free end of shaft 44a is threaded at 46 to receive a nut 54 to retain the associated parts together.

Adjacent end plate 51, sides 49 of box 47 are provided with upwardly struck parallel brackets 55 and 56 integral therewith, and extending upwardly to the same height as box end plate 50. Secured to the inner faces of brackets 55, 56 are parallel elongated horizontal bars 57, 58 having their extreme ends abutting the inner surface of end plate 43, and having secured between the

abutting ends a hexahedral plug 59 provided with a horizontal bore 59a in alignment with hole 45 in plate 43. A hollow sleeve member forming stud shaft 45a is secured to the abutting face of plug 59 with its affixed 5 end surrounding bore 59a and with its other end extending loosely through hole 45. A gear 60 is mounted on shaft 45a adjacent the outer face of end plate 43 and a nut 61 screwed on shaft 45a holds together shaft 45a, gear 60 and plug 59 with bars 57, 58. These elements 10 and box 47 taken together form the cradle 24 unitarily rotatable about axis Y'—Y'.

The above described converter linkage provides the impetus for rotating the cradle about axis Y'—Y', with the connection between the two structures comprising 15 a pin 62 extending through aligned holes 63 and 64 and 64a formed respectively in the apex of bell crank member 39 and in horizontal bars 57, 58, the shorter leg 39b of the bell crank extending upwardly and to the right as seen in Figure 1, and the apex fitting snugly between 20 bars 57 and 58. The upper end of leg 39b is bi-furcated as at 65 and each leg of the bi-furcation is provided with aligned holes 66 (one shown) to receive a pin 68 upon which is mounted a roller 70, which in turn is 25 adapted to bear against the flat abutting face of a slide member 71 adapted for reciprocable translation between bars 57 and 58, and guided for such translation by a cylindrical slide rod 72 secured to the face opposed to the roller abutting face thereof, and extending for reciprocation through hollow sleeve 45a. Slide 71 is also 30 provided with a portion 73 extending below the surfaces of bars 57, 58, and extending horizontally therefrom in a direction opposed to slide rod 72 is a second slide rod 74 reciprocable through a hole 75 in plate 51 and extending into box 47. A compression spring 76 surrounds 35 slide rod 72 and extends between slide 71 and plug 59 to bias slide 71 to the left as seen in Figure 1 and into continued abutting engagement with roller 70.

In describing the operation of the axis converter brief reference will be made to elements of the director apparatus which are not important to the invention on hand and have not been illustrated. Referring to Figure 1, the usual director includes handles (not shown) attached to the ends of shaft 8, readily accessible to an operator for turning the telescope 9 in elevation about an axis 40 through telescope shaft 8. The director is also equipped with a strap (not shown) connected to the rotating head and adapted to fit about the waist of the operator so that the pressure of his body assists the pressure upon the telescope handles to move the director head in train. 45 As the telescope is moved in elevation, and train, gearing connected to shaft 8, and to azimuth gear 3 drive synchro units or telemetric transmitters for transmitting elevation and azimuth orders to a gun mount computer. 50 As previously indicated these orders are related to a horizontal plane, or to the ground, and it is the purpose of the present invention to convert the elevation and azimuth readings to orders taken relative to a vertical plane perpendicular to the ground.

As the telescope is rotated in elevation, this rotation is 55 transmitted to "input elevation" axis X—X by virtue of the motion imparted to push-pull rods 18 and 19, and the action of pinions 15, 16 and racks 20, 21, 22 and 23. Arms 25 and 26 are accordingly rotated about this axis in either clockwise or counterclockwise direction as the case 60 may be, in parallelism with the line of sight of telescope 9, and this rotation is in turn transmitted to converter links 30 and 31 through pivot pin 27, imparting either thrust or a pull combined ordinarily with a rotation of block 36 about pin 38 to the connection with bell crank member 39. As a result of the swivel connection between gimbal 36 and bell crank member 39, and since bell crank member 39 is constrained against lateral movement because of pivot pin connection 65 62 with bars 57, 58, bell crank 39 will pivot either in a clockwise or counterclockwise direction to cause roller 70 to traverse the flat abut- 70 75

ting face of slide member 71, wherefore slide member 71 and rod 72 are caused to reciprocate either to the right or left assisted by the compressive action of spring 76. Since slide rod 74 is integral with slide member 71, it also reciprocates within hole 75 in plate 51. The axial translation of rod 74 may be taken off by suitable rack and gear mechanism (not shown) to drive telemetric transmitter means to convey such motion to a computer. The arrangement of the linkage is such that the longer leg 39a of the bell crank 39 defines the elevation angle with respect to a vertical plane, and the lateral movement of the slide defines a position or produces a signal which is proportional to the cosine of the elevation angle with respect to that vertical plane. This latter angle transmitted to the computer is sufficient for the desired purpose, as it may be there reconverted by mechanism similar to that shown to angular values.

The director head when turned in azimuth rotates about axis Y-Y, or the "input azimuth" axis of the director azimuth gear, as previously indicated, and is connected with a train of gears (not shown) for driving other synchro units (not shown) for transmitting azimuth orders with respect to the ground, to the gun mount or computer. As the azimuth gear rotates, brackets 10 and 11, which are integral therewith, also rotate about this axis to rotate the entire converter linkage to cause bell crank member 39 to rotate the entire cradle structure including gear 60, mounted in shafts 44a and 45a about azimuth output axis Y'-Y', and through gear 60, this movement in turn drives synchro units (not shown) to transmit azimuth orders relative to a vertical plane perpendicular to the ground, to a gun mount or computer. In other words, the motion of gear 60 produces a signal which is proportional to $\angle BAX$ as shown in Fig. 2. Still referring to Fig. 2 it will be seen that

$$(1) \quad \frac{\sin \angle PAC(PA)}{\cos \angle CAX(AC)} = \tan \angle BAX$$

since

$$\frac{PA}{AC} = \frac{1}{\cos \angle PAC}$$

Equation 1 becomes

$$(2) \quad \frac{\sin \angle PAC}{\cos \angle PAC \cos \angle CAX} = \tan \angle BAX$$

since

$$\frac{\sin \angle PAC}{\cos \angle PAC} = \tan PAC$$

Equation 2 becomes

$$(3) \quad \frac{\tan \angle PAC}{\cos \angle CAX} = \tan \angle BAX$$

Therefore, the rotation and pivoting of the telescope, azimuth and elevation movements respectively, operating on the axis converter linkage above described, produces a signal through movement of gear 60 which is proportional to the angle whose tangent is equal to the tangent of the angle of rotation, or azimuth, multiplied by the reciprocal of the cosine of the pivotal angle, or elevation.

In explaining the operation of the converter, it is to be noted that no mention has been made of any effect on the movement of the "output azimuth" axis when the telescope is moved in elevation. Likewise in moving the director head in azimuth only the corresponding effect on the "output azimuth" axis has been described. It is apparent that in view of the gimbal connection of the converter links to the bell crank member, and because of the restraint provided by the pivotal connection of the bell crank member with the cradle structure mounted on axis Y'-Y', a movement in elevation of the telescope will, in the normal operation of the directors, have some effect on the "output azimuth" axis also, and in like manner rotation of the director head in azimuth will also influ-

ence the "output elevation" axis. Figure 2 delineates graphically the elevation and azimuth angles of a line of sight with respect to the ground and vertical planes. Reference to this figure will serve to illustrate the effect of a change in the line of sight on the various angles shown. For example, AP is the line of sight, $\angle XAC$ denotes azimuth with respect to the ground plane and $\angle PAC$ represents the elevation with respect to the ground. $\angle PAB$ is the elevation as to a vertical plane perpendicular to the ground, whereas $\angle BAX$ represents azimuth as to this vertical plane.

When the telescope is moved in elevation only, $\angle PAC$ will change and $\angle XAC$ remains the same. The axis converter linkage will cause a change in both $\angle PAB$ and $\angle BAX$. So also when the telescope is moved in train $\angle CAX$ will change and $\angle PAC$ will remain the same, however both angles $\angle PAB$ and $\angle BAX$ will change. In other words, if the telescope is elevated without changing its direction in azimuth, the converter linkage will pivot the bell crank member to effect a corresponding change in the elevation of the line of sight with respect to the vertical plane. Simultaneously the action of the linkage will be transmitted to the bell crank member 39 through gimbal 36 to rotate cradle structure 24 about axis Y'-Y' to effect a small change in "output azimuth." In like manner, a change in train only of the telescope also effects a change in "output elevation" as well as the more noticeable change in "output azimuth."

There are however special exceptions to the above described movements in both "output elevation" and "azimuth output" for changes in direction of the telescope. The first exception is when the line of sight is at zero elevation, and $\angle PAC$ is zero. For this position of the telescope, the cradle structure is turned through an angle such that any change in "input azimuth" will effect a corresponding change in "output elevation" only. This is clearly seen by referring to Figure 2, since for this condition points (P) and (C) are co-incident and (B) now lies in the line of intersection of the ground and vertical planes, therefore a change in $\angle CAX$ affects only $\angle PAB$. The second exception obtains when the "input azimuth" angle is zero. In this position of the telescope, (P) and (B) are co-incident in the vertical plane and (C) lies in the intersection of the two planes between (X) and (A). Hence any change in elevation of the line of sight to change "input elevation" $\angle PAC$ will affect a corresponding change in "output azimuth" $\angle BAC$ only. In the linkage illustrated in Figure 1, when the telescope is set at zero azimuth, leg 39b of bell crank member 39 lies in the axis Y'-Y'. Hence any change in elevation of the telescope will have no translatory effect on slide member 72. However the linkage will serve to rotate the cradle about axis Y'-Y' to correspondingly change the "output azimuth" angle.

The above described axis converter linkage is illustrative of applicant's apparatus to convert line of sight readings with respect to a ground plane, to a vertical plane perpendicular to the ground. However the disclosed device is merely exemplary, and numerous other modifications and alterations of the same will be apparent to one skilled in the art. It is obvious that any such modification may be made without departing from the spirit and scope of the invention as defined in the following claims.

I claim:

1. An axis converter mounting a telescope rotatable in a first fixed plane and pivotable about an axis parallel to said first fixed plane and in a series of intersecting planes normal to said first fixed plane, and means responsive to the movement of said telescope to produce a signal proportional to the angle whose tangent is equal to the tangent of the angle of rotation multiplied by the reciprocal of the cosine of the pivot angle.

2. The converter in claim 1 wherein said means comprises linkage unitarily rotatable with said telescope about a common axis, and means connected to said telescope

pivoting means for pivoting said linkage about an axis parallel to and in vertical alinement with the pivotal axis of said telescope.

3. The converter in claim 2 including a cradle structure having a swivel connection with said linkage and rotatable in response to movement of said telescope and said linkage, about an axis parallel to said first fixed plane and defining output azimuth with respect to said vertical plane, and a slide connected to said linkage and horizontally reciprocable within said cradle in response to pivoting of said telescope to define output elevation with respect to said vertical plane.

4. An axis converter comprising a head rotatable in azimuth and mounting a telescope pivotable in elevation, said azimuth and said elevation being with respect to a ground plane, and means responsive to the movement of said head in azimuth and said telescope in elevation to produce a signal proportional to the angle whose tangent equals

$$\frac{\text{tangent of the angle of rotation}}{\text{cosine of the pivot angle}}$$

5. The converter in claim 4 wherein said means comprises linkage unitarily rotatable with said telescope about a common axis, and means connected to said telescope pivoting means for pivoting said linkage about an axis parallel to and in vertical alinement with the pivotal axis of said telescope.

6. The converter in claim 5 including a cradle structure having a swivel connection with said linkage and rotatable in response to movement of said telescope and said linkage, about an axis parallel to said ground plane and defining output azimuth with respect to said vertical plane, and a slide connected to said linkage and horizontally reciprocable within said cradle in response to pivoting of said telescope to define output elevation with respect to said vertical plane.

7. An axis converter mounting a telescope rotatable in a horizontal plane defining input azimuth with respect to the ground, and pivotable in a plurality of vertical intersecting planes defining input elevation with respect to the ground, and means responsive to said input azimuth and said input elevation to produce a signal proportional to the angle whose tangent equals

$$\frac{\text{tangent of input azimuth}}{\text{cosine of input elevation}}$$

8. The converter in claim 7 wherein said means comprises linkage unitarily rotatable with said telescope about a common axis, and means connected to said telescope pivoting means for pivoting said linkage about an axis parallel to and in vertical alinement with the pivotal axis of said telescope.

9. The converter in claim 8 including a cradle structure having a swivel connection with said linkage and rotatable in response to movement of said telescope and said linkage, about a horizontal axis defining output azimuth with respect to said vertical plane, and a slide connected to said linkage and horizontally reciprocable within said cradle in response to pivoting of said telescope to define output elevation with respect to said vertical plane.

10. In a director, a head rotatable about a vertical axis, a telescope mounted on said head and pivotable about a horizontal axis, the rotation of said head defining the input azimuth of the line of sight of said telescope with respect to the ground, and the pivoting of said telescope defining input elevation of the line of sight of said telescope with respect to the ground, a cradle mounted on said director rotatable about a horizontal axis, the rotation of said cradle defining output azimuth of the line of sight of said telescope with respect to a vertical plane per-

pendicular to the ground, a slide supported on said cradle for horizontal reciprocation with respect thereto, the position of said slide defining output elevation of the line of sight of said telescope with respect to said vertical plane, linkage means connecting said rotating head and said cradle for transferring the rotation of said head to said cradle, there being a connection between said telescope and said linkage and between said linkage and said slide for transferring the pivoting of said telescope to said slide.

10 11. Apparatus for tracking the present position of a moving target in space comprising, a director having a head rotatable about a vertical axis, a telescope mounted on said head and pivotable about a horizontal axis, the rotation of said head and the pivoting of said telescope defining azimuth and elevation of the line of sight of said telescope with respect to the ground, and mechanical linkage means integrally rotatable with said head and movable in response to the pivoting of said telescope for converting said azimuth and elevation of the line of sight of said telescope to azimuth and elevation referred to a vertical plane perpendicular to the ground.

15 12. The apparatus in claim 11 with cradle means rotatable about a horizontal axis, and including means horizontally slidable mounted on said rotatable cradle, said rotatable cradle defining azimuth with respect to said vertical plane, and said slidable means defining elevation with respect to said vertical plane, and swivel means connecting said linkage with said rotatable cradle and said slide.

13. The apparatus in claim 12 wherein said rotatable 30 cradle comprises a pair of horizontally spaced vertically upstanding brackets mounted on said director, each said bracket having horizontally directed holes for receiving opposed stud shafts, said cradle being mounted for horizontal rotation on said stud shafts and between said 35 brackets.

14. The combination in claim 13 including a pair of spaced horizontal bars forming a part of said cradle and defining a guide track for said slide, a bell crank member having its apex received in said track and pivotally mounted on said horizontal bars, said bell crank member having one leg swivelly connected to said linkage and the other leg with its free end abutting a vertical face on said slide member.

15. An apparatus for tracking the present position of a 45 moving target in space comprising, a plate rotatable about a vertical axis, a telescope mounted on supports secured to the top surface of said plate and pivotable about an axis parallel to said plate, means driven by the pivotable movement of said telescope for transmitting elevation with respect to the ground of a target in the line of sight of said telescope to a gun mount, second means driven by the rotation of said plate for transmitting azimuth with respect to the ground of a target in the line of sight of said telescope, a cradle mounted on said apparatus and rotatable about an axis parallel to the ground, a gear mounted on said cradle axis unitarily rotatable therewith, third means driven by said gear for transmitting azimuth with respect to a vertical plane perpendicular to the ground of a target in the line of sight of said telescope, a slide mounted on said cradle rotatable therewith and horizontally reciprocable with respect thereto, fourth means driven by said slide for transmitting elevation with respect to said vertical plane of a target in the line of sight of said telescope, and axis converter linkage connecting said telescope and said plate with said cradle and said slide whereby movement of said telescope to obtain elevation and azimuth with respect to ground of a target in the line of sight of said telescope is converted to azimuth and elevation with respect to said vertical plane.
